UNITED STATES PATENT OFFICE.

CHRISTOPHER D. O'CONNOR, OF CHICAGO, ILLINOIS.

SHOE-FASTENER.

1,325,409.

Specification of Letters Patent.

Patented Dec. 16, 1919.

Application filed September 14, 1918. Serial No. 254,059.

To all whom it may concern:

Be it known that I, CHRISTOPHER D. O'CONNOR, a citizen of the United States, residing at Chicago, in the county of Cook and State of Illinois, have invented a new and useful Shoe-Fastener, of which the following is a specification.

The subject of this invention is a shoe fastener.

10 The main object of the invention is the provision of a fastener which will take the place of hooks or eyelets.

Another object of the invention is the provision of a fastener which will permit a 15 shoe to be quickly laced.

The invention also contemplates generally improving the construction and enhancing the utility of fasteners.

With the foregoing and other objects in view, which will appear as the description proceeds, the invention resides in the combination and arrangement of parts and in the details of construction hereinafter described and claimed, it being understood 25 that changes in the precise embodiment of the invention herein disclosed can be made within the scope of what is claimed without departing from the spirit of the invention.

30 A practical structure for carrying out the invention is shown in the accompanying drawing, wherein:—

Figure 1 is a fragmentary view in front elevation of a shoe with a fastener constructed in accordance with the invention 35 in place thereon;

Fig. 2 is a similar view showing a different arrangement of the fastener;

Fig. 3 is a view in rear elevation of the fastener;

40 Fig. 4 is a side elevation of the same.

Referring to the drawing by numerals of reference:—

A fragment of the front portion of the upper of a shoe is indicated at 1, and a lace 45 2 is passed through the eyelets 3 in the usual manner for the purpose of drawing the edges of the upper 1 together.

The fasteners 4 are secured along the meeting edges of the uppers 1 by means of stitching 5, or otherwise. The remote edges 50

of these fasteners 4 are curved slightly and undercut, as at 6, to provide the overhanging flange 7 beneath which the lace 2 may be drawn.

As will be seen, the fasteners are arranged in pairs, and are of considerable extent, so that two pairs of fasteners will occupy practically the whole of the meeting edges of the uppers of a shoe. The fasteners are formed of leather, or other suitable material, and may be scored, as indicated at 8, to permit the fastener to give with the movements of the foot and so assure ease of movement.

With the fasteners arranged as shown in Fig. 1, the lower part of the shoe is laced through the eyelets 3 and the upper portion is held together by bringing the laces about the fasteners 4, beneath the flanges 7, and then tying the laces above the fasteners as shown.

With the arrangement of fasteners shown in Fig. 2, the laces 2 are drawn about the fasteners 4, beneath the flanges 7, and then crossed between the opposed ends of the pairs of fasteners, and drawn about the upper fasteners 4, and then tied above the fasteners, as shown.

This draws the members of each pair of fasteners together and so holds the meeting edges of the uppers of the shoes closely together.

Having thus described the invention, what is claimed as new and sought by Letters Patent, is:—

In combination with the opening of a shoe upper, elongated strips secured to the upper and having straight inner edges alining with the edges of the opening and having curved outer edges undercut to form an overlying edge, and a lace engaging the undercut of said strips and retained by said overlying edge.

In testimony that I claim the foregoing as my own, I have hereto affixed my signature in the presence of two witnesses.

CHRISTOPHER D. O'CONNOR.
